Primary Examiner—Sandra L. Morris

(57) **CLAIM**

The ornamental design for a mounting frame, as shown and described.

DESCRIPTION

FIG. 1 is a right side elevational view showing the right loader support of the new design, the broken line showing of the tractor and loader being for the sole purpose of showing the design in its environment of use and forming no part of the claimed design.

FIG. 2 is a view like FIG. 1 but showing the left loader support of the new design.

FIG. 3 is a left front perspective view of the left loader support.

FIG. 4 is a left side elevational view of the right loader support.

FIG. 5 is a bottom perspective view of the left loader support; and,

FIG. 6 is a left side elevational view of the left loader support.
